UNITED STATES PATENT AND TRADEMARK OFFICE
CERTIFICATE OF CORRECTION

PATENT NO. : Des. 604,709 S
APPLICATION NO. : 29/313800
DATED : November 24, 2009
INVENTOR(S) : Koigi

Page 1 of 1

It is certified that error appears in the above-identified patent and that said Letters Patent is hereby corrected as shown below:

In item (12) on the Title Page, the inventor's last name should be --Koigi--.

In item (76) on the Title Page, the inventor's last name should be --Koigi--.

Signed and Sealed this

Sixteenth Day of March, 2010

David J. Kappos
Director of the United States Patent and Trademark Office
